UNITED STATES PATENT OFFICE.

JAMES F. THOMAS, OF WINDSOR, ONTARIO, CANADA.

POWER-GENERATING MECHANISM.

Original application filed April 8, 1922, Serial No. 550,753. Divided and this application filed October 21, 1922. Serial No. 596,080.

To all whom it may concern:

Be it known that I, JAMES F. THOMAS, a subject of the King of Great Britain, residing at Windsor, in the Province of Ontario 5 and Dominion of Canada, have invented certain new and useful Improvements in Power-Generating Mechanism, of which the following is a specification.

This invention relates to rotary motor 10 mechanism particularly adapted for use with power generating mechanism, and the primary object of the same is to provide a rotor mechanism adapted to receive compressed air delivered thereto from a prime 15 compressing means forming part of the power generating mechanism, or the water that may be elevated to or forced into a reservoir means, and to utilize the power generated by the rotor for general service. 20 A further object of the invention is to simplify and economize in the general construction and organization of the parts of a rotor mechanism adapted for use with power generating mechanism and at the same time reinforce or strengthen the several parts to 25 withstand wear and tear and pressures to which the parts may be subjected during the operation of the rotor, and also to render the operation of the rotor effective and positive as a power generating means. 30

With these and other objects and advantages in view, the invention consists in the construction and arrangement of the several parts which will be more fully hereinafter 35 described and claimed.

In the drawings:

Fig. 1 is a sectional elevation of the improved rotor mechanism and connections between the same and storage reservoir, the 40 rotor mechanism being shown in transverse vertical section and parts of the pipe attachments broken away;

Fig. 2 is a horizontal section taken through the center of the rotor and its casing as shown by Fig. 1;

Fig. 3 is a plan view of the rotor and a portion of its shaft removed from the rotor casing;

Fig. 4 is a top plan view of one of the 50 top inlet plates of the rotor;

Fig. 5 is an enlarged transverse vertical section on the line 5—5, Fig. 3; and

Fig. 6 is a side elevation of the bottom portion of the rotor casing.

55 This application constitutes a division of

the subject-matter originally disclosed by my Patents Nos. 1,441,135, Jan. 2, 1923, and 1,430,416, Sept. 26, 1922.

In my Patent No. 1,430,416, above noted, a converging connection is embodied for the 60 compressed air or water elevated thereby and this connection is attached to a coupling 76 connected to the bottom of a reservoir 77 preferably disposed in upright position and serving as a storage means. The surrounding walls 78 of the reservoir are preferably formed of plastic material with a bottom closure plate 79 and a cap plate 80. On the inner side of one of the walls 78 rail ribs 81 are secured and engage suitable 70 grooves 82 formed in the adjacent side of a gravitating piston 83 for guiding the said piston in its action and holding the same in central position within the reservoir. The piston 83 is prevented from lowering beyond 75 a predetermined point within the cylinder 77 by a stop pin 84. The air under pressure, or the water desired to be stored in elevation, passes through the coupling or supply connection 76 and enters the lower portion of 80 the reservoir or storage tank 77. The function of the piston 83 is to maintain the air stored in the reservoir or tank under certain pressure, the pressure stored within the reservoir or tank when sufficiently strong to 85 overcome the weight of the piston 83 gradually raising the latter, and as a consequence, the weight pressure on the air stored in the cylinder will be increased and perform an important function relatively to the pressure of the air in the said reservoir or tank. 90

From the reservoir or tank 77 the stored air under pressure will be liberated for a practical service in a manner which will be presently explained. Water may be likewise supplied to the reservoir 77 and similarly distributed or discharged from the latter for operation of the motor means including a rotor.

The preferred form of rotor and rotor enclosure which is operatively associated with the tank or reservoir 77 and adapted to be actuated or rotated either by air delivered thereto from the reservoir or by water stored in said reservoir consists of a plastic casing 105 85 of any suitable length and having an approximately semi-cylindrical bottom portion 86 with a central outlet 87 having flared walls 88 adjacent thereto. The casing 85 also has plastic ends 89, as shown by Fig. 110

2, and in the preliminary structure of the said casing 85 as a whole, metal plates 90 are applied in the mold at the ends and have upright brace bars and key devices 91 attached thereto. When the cement or plastic material is inserted in the mold, it is disposed between the plates 90 and brace bars and key devices 91 become imbedded therein, and thereby hold the said plates in fixed 5 associated relation with the ends 89 of the casing. During the molding operation of the casing 85 including its ends 89, a shaft 92 is placed in proper position relatively to the interior of the mold, the plates 90 having 10 slots 93 formed therein and opening through the upper edges to permit the shaft to be let down into position relatively to the said plates, and when the cement or plastic material is disposed in the mold between the plates 90 it fills over the shaft at 15 the ends, or closes the slots 93. The shaft 92 is projected through openings in the ends 89 of the same diameter as the shaft, the said openings being formed by turning the shaft in the cement or plastic material while the latter is soft. It will be understood that suitable stuffing boxes and bearing devices may be provided in connection with the shaft at the ends if found necessary, to 20 render the casing ends 89 both air and water tight around the shaft where the latter projects outwardly through the said ends. However, in view of the structure of the rotor carried by the shaft 92, stuffing boxes 25 or other similar devices will be unnecessary, as the assemblage of the ends of the rotor structure with the inner sides or ends or end walls 89 of the casing 85 will be such as to make it possible to dispense with stuffing 30 boxes or like devices. Throughout the length of the casing or casing body 85, including the ends 89 thereof, reinforcing rods 94 and also other reinforcing structures 35 commonly used will be introduced, to give 40 the body of the casing sufficient rigidity as well as strength and durability to resist pressure from within and overcome any tendency to fracture or breakage of the said casing. These rods 94, which run lengthwise 45 of the casing 85 or through the side portions of the latter, are secured against the end plates 90, as shown by Fig. 2. Below the outlet 87 and the flared walls 88 at the bottom of the casing 85 a longitudinal 50 discharge outlet 95 is formed, as clearly illustrated by Fig. 6, said outlet extending fully between the opposite ends 85 and whereby when water is used as the motive medium, the discharge of the water through 55 the outlet 87 may be quickly relieved or carried away from the lower portion of the casing. The lower portion 86 of the casing, as hereinbefore explained, is semi-cylindrical but the upper portions of the sides of 60 the casing are vertically straight, as at 95^a,

opposite shoulders 96 being produced at the point of intersection of the lower opposite curved walls and the upper vertical walls. The lower curved walls have the rotor elements closely engaging the same, and the 70 upper vertical walls provide for a practical introduction or feed of the motive medium, such as air or water, to the actuating elements of the rotor. On top of the casing 85 and extending full length thereof are inlet 75 devices 97 of similar structure, said inlet devices as shown by Fig. 4 consisting essentially of rectangular plates with central inlet collars 98 opening into a distributing chamber 99 having side walls 100 downwardly converging towards a comparatively reduced feed slot 101. The walls 100 also converge from the center of each plate towards the opposite ends of the latter, as at 102, see Fig. 4 in dotted lines. The inlet devices 97 constitute cover plates for a portion of the top of the casing 85 and the inner flanges 103 of these plates provide the side walls for a top outlet 104, which extends the full length of the plastic casing 90 85. The outlet 104 is in the form of an elongated metal tube having base flanges 105 which are secured on the flanges 103 of the plates 97 by suitable fastening devices 106, as shown by Fig. 1. The interior of the collars 98 are threaded and connected thereto are the lower terminals of a U-pipe 107 which has the vertical legs 108 thereof each provided with a cutoff valve 109, and whereby the flow or supply of the motive medium such as air or water to either side of the interior of the casing for controlling the operation of the rotor in reverse directions is regulated. To the top or upper head member of the U-pipe 107 a suitable supply 95 pipe 110 is connected and also attached to and communicates with the interior of the reservoir or tank 77 at a point above the bottom of the latter.

The shaft 99 has a rotor 111 keyed or 110 otherwise fastened thereto and composed of a series of hub sections 112 fitted over the shaft in end to end relation as shown by Figs. 2 and 3, and each having a plurality of T-angle-arms 113 projecting therefrom, there being six arms in the present instance on each hub section. Applied to the angle arms 113 are thin sheet metal plates 114 and 115, as shown by Fig. 5, the plates being disposed between the stem flanges 116 of the T-arms 113 and suitably secured against the horizontal or right-angular members 117 of said T-arms. The plates 115 are each of a width just equal to the distance between the stem members 116 and snugly abut against the latter, and each plate or sheathing 114 is continuous across its group of horizontal members 117. By this means a space is formed between the two series of plates 114 and 115, and in this space is in- 125 130 135

introduced a filling 118 of cement or plastic material, so as to solidify the structure and at the same time reduce the weight without detracting from the necessary strength and durability of each blade organization of the rotor, which is produced by the structure just explained. The stem members 116 stand outwardly and project beyond the plates 115 and reinforce the blades of the rotor, and coating with the horizontal integral members 117 prevent buckling or distortion of the blades. The outer edges of the plates 114 as shown by Fig. 1 project slightly beyond the edges of the plates 115 and cement or plastic fillings 118, so as to closely contact with the curved walls of the lower semi-cylindrical bottom portion 86 of the casing 85, and in the preliminary construction of the casing these plates are caused to form the said curved walls while the material of the latter is sufficiently soft by rotating the shaft 92 to which the hub sections 112 and the parts carried thereby, or the blades, are primarily secured. By means of this preliminary preparation a close fitting of the projecting ends of the plates 114 and the curved end walls of the lower semi-cylindrical portion 86 of the casing is produced. The rotor blades constructed as just explained are alternatively cut away or slotted, as at 119, adjacent to the hub sections. These slots 119 extend inwardly about midway of the ends of the rotor blades, the slot of one blade being over a closed or unslotted portion of the adjacent blade, and so on around the series of adjacent blades. The object of these slots is to particularly adapt the rotor for water impact and prevent the formation of resisting cushions at the inner portions of the blades close to the hub sections, the slots relieving water that may accumulate at the inner portions of the blades and thereby insuring least resistance to a sensitive operation or drive of the blades by the impact of incoming water thereagainst. Likewise, these openings equally well function when compressed air is introduced into the casing 85 as the operating medium, the air passing in close to the hub sections, or between the reduced portions of the angular spaces between the blades, escaping upwardly through the openings of the blades above those below and liberated at the top portions of the rotor casing, or through the outlet means or device 104. The outer ends of the outermost hub sections 112 extend into the inner sides of the end plastic walls 89 of the rotor casing 85, as at 120, see Fig. 2, and form tight joints around the shaft or adjacent to the points where the latter extends outwardly through the ends 89. This association of the outermost hub sections 112 with the ends of the casing will obviate leakage from the interior of the casing around the shaft, and as hereinbefore explained, any suitable packing means may be introduced at this point to increase the non-leaking efficiency of these associated end parts.

The operation of the improved rotor is very simple. The stored air or water in the reservoir 77 is permitted to pass to the rotor through the medium of either one of the vertical legs 108 of the U-pipe 107 by opening the one valve 109, the other similar valve being closed. When air is stored in the reservoir or tank 77, it is delivered in compressed form into the said tank or reservoir against the weight of the gravitating piston 83, which maintains the pressure of the air at a maximum. When it is desired to use the compressed air, either one of the valves 109 is opened, and if the one at the right is opened as shown by Fig. 1, air will be admitted into the distributing chamber 99 at the right of the rotor and then through the constricted outlet 101 between the downwardly converging walls 100 and impact against the blade of the rotor nearest the said outlet 101. The incoming air striking the rotor blade will force the rotor 111 and its shaft 92 around to bring a succeeding blade into position for impact of the air under pressure, and so on throughout the whole series of blades. The incoming air striking each blade will expand and be liberated in an upward direction between the outer extremity of the next blade above and the innermost inclined wall 100, in view of the fact that the inner extremity of the blade clears the said inclined wall such a distance as to permit free escape of the air, it being preferred that the inlet 101 be proportionately smaller than the open space between the outer end of each blade and the innermost wall 100. The air entering the casing 85 and striking the successive blades will also be liberated through the slots or openings 119 at the inner portions of the several blades and pass upwardly through the common outlet 104, and from this outlet the air may be conveyed to a further means of storage or be utilized for any other purpose desired. In reversing the rotor the valve 109 on the right is closed and the similar valve on the left as shown by Fig. 1 is opened, thereby causing an impact of the air against the blades on the left side of the rotor and a consequent reversal in the direction of rotation. This simple method of reversing the rotor will be exceptionally advantageous in operating different kinds of mechanism, and such reversal may be expeditiously effected without requiring manipulation of complex devices.

The water is stored in the reservoir or tank 77 the same supply operation to the rotor 111 ensues through either of the inlets 101 by way of either distributing chamber 99 in accordance with the open or closed con-

dition of the valves 109 controlling supply to the respective chambers 99, and the water after striking the successive blades will pass down through the openings alternately arranged in the blades as hereinbefore explained, to avoid crowding or pocketing and setting up a cushioning or pressure-resisting action at the center of the rotor. Moreover, the water which does not pass downwardly through the openings 119 in the blades will follow around with the several blades until the lower discharge outlet 87 is reached, when the water will be completely liberated from the blades. The water passing downwardly through the blades will in like manner flow out through the lower discharge opening 87 and then through the general outlet opening 95 below the said outlet 87. It is obvious that the proportions and dimensions of the several parts of the motor and its accessories may be varied to adapt the same to different uses without departing from the nature or spirit of the invention.

What is claimed as new is:

- 25 1. In a mechanism of the class specified, a motor consisting of an enclosing casing constructed of plastic material and having upper opposite straight side walls and lower curved walls, metal top plates having collars projecting upwardly therefrom, the top of the casing having oppositely disposed distributing chambers confined between inwardly and longitudinally converging walls with contracted slot outlets, the enclosing casing of the motor mechanism having top and bottom continually open outlets, a rotor within the casing comprising a plurality of blades alternately having relief openings adjacent the center of the rotor, and valved supply connections associated with said collars for delivering the operating medium under pressure to the distributing chambers for passage between the converging walls and through the contracted outlets to engage and forcefully impact against the blades of the rotor.
- 30 2. In a mechanism of the class specified, motor mechanism comprising a casing formed of plastic material and having lower opposite side curved walls and upper

straight walls, end plates applied against the ends of the casing, upright reinforce devices imbedded in the plastic material at the ends of the casing and secured to the plates, reinforcing means extending through the walls of the plastic covering and secured to the plates, top cover plates having connecting means and converging outlets depending into the upper part of the casing, the casing also having continually open upper and lower discharge outlets, pipe connections attached to the cover plates for supply of the operating medium, the pipe connections having independent valves in parts thereof for controlling the feed of the operating medium to the motor, and a rotor within the casing having blades and a shaft projecting outwardly through the ends of the casing, the operating medium being delivered into the motor mechanism through the converging outlets to impact against the blades of the rotor.

3. In a mechanism of the class specified, a rotary motor comprising a casing having top plates with downwardly converging walls extending into the interior of the casing and forming constricted inlets, the top and bottom of the casing having continuously open outlets for the liberation of different kinds of operating medium, a rotor mounted in the casing and having a shaft extending through the ends of the latter, said rotor being provided with a series of blades comprising hub sections with radiating T-arms and upper and lower plates applied to the arms, the plates in alternation throughout the series of blades being formed with openings in their inner portions near the hub of the rotor, the outer ends of a part of the plates projecting beyond the remaining portions of the blades and serving to shape a portion of the interior of the casing for operation of the rotor, and valved connecting means for supplying motive medium to the motor and associated with the said cover plates.

In testimony whereof I affix my signature.

JAMES F. THOMAS.
